UNITED STATES PATENT OFFICE.

THEODOR D. EISNER, OF WOODHAVEN, NEW YORK, ASSIGNOR TO MARTIN ADOLF EISNER, OF WOODHAVEN, LONG ISLAND, NEW YORK.

EMBROIDERY-FRAME.

1,310,392.

Specification of Letters Patent. Patented July 15, 1919.

Application filed April 7, 1917. Serial No. 160,378.

To all whom it may concern:

Be it known that I, THEODOR D. EISNER, a citizen of the United States, and resident of Long Island, in the State of New York, 5 city of Woodhaven, have invented certain new and useful Improvements in Embroidery-Frames, of which the following is a specification.

The present invention relates to improvements in embroidery frames, and more particularly such frames for use in embroidery machines, either of the hand or shuttle type, an object of the invention being to provide such frames by which small pieces of material may be simultaneously embroidered with the same pattern in a manner most effective for carrying out the embroidering operation, and with which the loose portions of the material may be so held as to be entirely out of the path of the embroidery needles.

A further object is to provide such a frame which may be used for different sizes of material by the insertion or removal of 25 spanning bars. With other frames at present in use the material is apt to become mutilated by reason of the holding means employed, and it is therefore an object of the present invention to so construct the holding 30 means as to in no way harm the material.

With these and other objects in view, embodiments of my invention are shown in the accompanying drawings, and these embodiments will be hereinafter more fully described with reference thereto, and finally pointed out in the claims.

In the accompanying drawings;

Figure 1 is a plan view of my improved frame with parts broken away, and showing 40 at the left hand portion of the figure an attachment for use in embroidering corners, such as the corners of handkerchiefs;

Fig. 2 is a vertical sectional view along the line 2-2 of Fig. 1;

Fig. 3 is a partial end and partial sectional view taken along the line 3-3 of Fig. 1;

Figs. 4, 5 and 6 are detail views of one spacing strip employed, showing the top, 50 side and end of the same;

Figs. 7 and 8 are side views of the spring bars employed;

Figs. 9 and 10 are top and end views respectively, of the surplus material containing member;

Figs. 11 and 12 show modified forms of spring bar holding means;

Fig. 13 is a plan view of a modified form of frame;

Fig. 14 shows an end view of a modified form of channel bar;

Fig. 15 is a sectional view along the line 15-15 of Fig. 1, and

Fig. 16 is a detail sectional view of a pivot screw employed in my improvements.

Similar reference characters indicate corresponding parts throughout the several figures of the drawings.

Referring to the drawings, and more particularly to Figs. 1 to 3 thereof, an embodiment of my invention comprises a pair of spaced and parallel rails 20 and 21 provided respectively with recesses 22 and 23, said recesses being spaced apart a distance corresponding to one unit, that is, a rapport starting from the first recesses 22 and 23 will be 4/4, 8/4, 12/4, 16/4, 20/4, etc. This arrangement may be varied if desired. Thus the rapport may be 6/4, 13/4, 18/4, 24/4, 30/4, etc. U-shaped channel bars 24 and 25 are secured at their extremities in the end recesses of the rails 20 and 21 by means of screws 26, thereby forming a rigid rectangular frame provided intermediate the said end channel bars with a plurality of recesses 27 in which additional removable channel bars 28 may be inserted in any of the recesses as desired, according to the size of the material to be embroidered.

All the recesses in the rail 20 are closed at their ends by means of a plate 29, and a holding strip 30 is secured at the upper side of the rail 20 which extends over the ends of the recesses 22, serving to hold the additional channel bars in place at one end. Recesses 31 and 32 are provided respectively in the rails 20 and 21 at one side of the recesses 22 and 23, and serve as sockets for the ends of surplus material holding bars 33 which may be either of the form shown in Figs. 9 and 10, in which the same has an inverted U-shape in cross-section, as shown at the left hand portion of Fig. 1, and in detail in Figs. 4, 5 and 6, or which may be a plain

spring bar 33, as shown adjacent the right hand channel bar 25 in Fig. 1. One longitudinal edge of the said bars 32 is bent upon itself as at 34, so that this edge which is free will not cut or injure the material.

Grooves 35 and 36 are provided on the inner portions of the rails 20 and 21, holding fingers 38 and 39 being pivotally arranged upon the rails in such manner as to be turned 10 above the grooves for holding therein a spring metal strip 37 which is preferably covered with rubber or the like, and beneath which the surplus material at the upper and lower ends of the cloth is placed. The holding fingers are preferably pivoted by means 15 of a novel pivot screw 38^a (Fig. 16) provided with a cup-shaped bushing 38^b.

Where the recesses 22 and 23 are intermediate the adjacent channel bars the inner 20 ends of the recesses are closed by means of a closure member 40, which is provided at its upper end with a hook shaped portion which engages with the inner edge of the rails, and fits into the grooves 35 and 36, the lower 25 end fitting into a retaining strip 41 secured to the lower portion of the rails, thus a smooth surface is provided for the edge of the material.

Pins 42 and 43 are transversely arranged 30 at the ends of the channel bars, disposed in the rail 20, the pin 42 being at the upper portion of the channel bar, while the pin 43 is at the lower portion. Intermediate the same there is provided a pin 44 upon which are 35 pivotally mounted the eyelet ends 45 of two spring bars 46 and 47, shown in detail in Fig. 7. These bars are covered with rubber tubing or the like 48, to protect the material held thereby.

40 A spacing strip 49 having a central longitudinal web 50 formed by bending, is placed in the channel bars, the spring rods 46 and 47 being disposed at each side of the web 50. The ends of the spring rods 46 and 47 are forced 45 down and are held by means of a fork-shaped key member 51, which engages straps 52 and 53 secured to the rail 21 by means of screws 54, and disposed at each side of the recess 23. The pins 42 and 43 are used when 50 desired for retaining in the channel bars additional holding strips, such for instance as the spring strip 55 shown in the second channel bar, Fig. 1, and in section in Fig. 2, this strip also being shown in detail in Fig. 8.

55 The operation of this embodiment of my invention is as follows:—The removable channel bars 27 are placed in the proper recesses according to the size of the material to be worked on, which in the present illustration is relatively thin material, such for instance as silk, linen or the like, and the end of the material is first laid over the end channel bar with the spring rods 46 and 47 raised. The surplus material is tucked into 60 the U-shaped member 32, as clearly shown in

Fig. 3, and the rods are then forced downwardly, tightening the material across the web of the member 49, the ends of the rods being then secured in place by the key 51. The material is then spanned to the next 70 channel bar where it is held in place by the spring rods 46, the surplus being held by means of the spring strip 55. The upper and lower ends of the material are tucked into the grooves 35 and 36 and are held 75 therein by the strips 37. Where the material is to be embroidered only at the corner, an auxiliary bar 56 is secured across the channel bars by means of set-screws 57^a in the turned up ends 57 of the said bar which 80 engage the end channel bars 24 and 25, and this bar is provided with a plurality of slots 58 or recesses as at 57^a, in which spring clips 59 are secured by means of lugs 60 on the said clips, which are placed in the slots as 85 shown in dotted lines, Fig. 1, and then turned into position, the lugs then being locked in place. In order to permit of the lower half of the spring rods being operated 90 separately from the upper half, I employ a clip 80 (Figs. 1 and 15) having at each side downturned portions 81 and 82, having recesses 83 which engage the bar 56. One edge of the clip is provided with a lug 84 which 95 engages the spring bars, while the other edge is provided with recesses 85 which permits of the lower half of the bar being sprung up, as clearly shown in Fig. 15, to allow cloth to be spanned at the lower half of the frame.

In the spanning of the material as above 100 pointed out, using the full width of the frame, this strip it will be understood, is removed. The next piece of material is held in the channel bar 27 by means of the spring rod 47, the surplus material being tucked 105 into the U-shaped member 32, the material then being spanned across to the next channel bar, the spanning of the various pieces of material being carried out in the same manner entirely across the frame. The 110 frame is preferably about 56 inches long, but may be longer or shorter if desired, and the recesses 22 and 23 are about an inch apart.

Upon the rail 21 there is provided at suitable intervals, blocks 61 so that the frame 115 may be set on end without disturbing the projecting ends of the spring rods.

In Figs. 11 and 12, I have shown modified holding means for the ends of the spring rods, the form shown in Fig. 11 consisting 120 of a pivoted plate 62 having a recess 63 therein, which may be engaged with the ends of the rods. In Fig. 12 a plate 64 secured at the end of the recess 23 is provided with a recess 65 therein, having a restricted 125 opening 66, thereby providing retaining lugs 67 and 68, beneath which the ends of the spring rods may be placed.

In Fig. 13, I have illustrated a slightly modified form of frame, especially intended 130

for embroidering the corners of handkerchiefs and the like, which consists of end rails 69 and 70, provided at suitable intervals with channel bars 71, in which are pivotally secured rods 72. These channel bars 71 are of relatively greater depth than the width, and the rods 72 which have their edges uppermost, are provided with rubber covering 73, and fit snugly into the channel bars. The free ends of the rods 70 are held in place by means of pivoted retaining members 74, and the extremities 75 of the said rods are twisted to form suitable handles. Spring clips 76 are provided upon the rail 69 intermediate the channel bars, for holding the corner of the material to be embroidered.

In Fig. 14, I have shown in end view, a modified form of channel bar, in which the same takes the form of the letter **S**, providing a **U**-shaped channel 77 for retaining the material, and an inverted **U**-shaped channel 78 for receiving the surplus material.

It will be understood that in either of the embodiments of my invention illustrated, the channels may be of suitable size to receive either one or a plurality of spring bars, the channels being preferably about a quarter of an inch in width for single spring bars, and about one-half an inch in width for double spring bars. Also it will be understood that the spring bars may be used either alone or in conjunction with the other holding strips, such for instance as the strip 49 or the strip 55, depending upon the class of material being worked upon, and the surplus material may be held either by a **U**-shaped member 32, or the spring strip 33. The spring bars need not be hinged, but may have their ends insertible beneath the holding pins.

I have illustrated preferred and satisfactory embodiments of my invention, but it is obvious that changes may be made therein within the spirit and scope thereof, as defined in the appended claims.

I claim:

1. A frame for holding materials to be embroidered, comprising a pair of spaced longitudinal rails, channel bars permanently secured between the ends of said rails forming a permanent rectangular frame, a plurality of spaced channel bar receiving means on said rails intermediate said permanent channel bars, removable and temporary channel bars adapted to be placed in selectively spaced relation between said permanently secured channel bars and adapted to be held in said receiving means to form between said end channel bars rectangular spaces of variable width, and means for securing material to be embroidered within said channel bars.

2. A frame for holding materials to be

embroidered, comprising a pair of spaced longitudinal rails, channel bars permanently secured between the ends of said rails forming a permanent rectangular frame, said longitudinal rails being provided with a plurality of spaced recesses intermediate said channel bars, removable and temporary channel bars adapted to be selectively mounted in said recesses to form between said end channel bars rectangular spaces of variable width, and means in said channel bars adapted to secure material to be embroidered therein.

3. A frame for holding materials to be embroidered, comprising a pair of spaced longitudinal rails, channel bars permanently secured between the ends of said longitudinal rails forming a permanent rectangular frame, a plurality of spaced channel bar receiving means on said rails, intermediate said permanent channel bars, removable and temporary channel bars adapted to be selectively mounted intermediate said permanently secured channel bars in spaced relation and adapted to be held in said receiving means to form between said channel bars rectangular spaces of variable width, and means for securing material to be embroidered within said channel bars, comprising spring rods bowed in their untensioned position, and means for holding said spring rods tensioned and relatively straight within in said channel bars.

4. A frame for holding materials to be embroidered, comprising a pair of spaced longitudinal rails, channel bars secured transversely between said rails and in spaced relation with each other, bow-spring means within said channel bars, and means adapted to retain the ends of said bow-spring means under tension within said channel bars to hold the material to be embroidered therein.

5. A frame for holding materials to be embroidered, comprising a pair of spaced longitudinal rails, channel bars permanently secured between the ends of said rails, removable and temporary channel bars mounted intermediate the said permanently secured channel bars in spaced and variable relation, and means for securing material to be embroidered within said channel bars, comprising an elongated spring member, means on one end of said channel bars adapted to retain one end of said spring member, means on the other end of said channel bars adapted to retain the other end of said spring member upon tensioning of said spring member.

6. A frame for holding materials to be embroidered, comprising spaced longitudinal rails, channel bars permanently secured between the ends of said rails, removable channel bars adapted to be mounted intermediate said permanently secured channel bars in spaced relation, and a transverse rail

adapted to be placed intermediate the ends and relatively straight within said channel of said channel bars, and provided with channel bar. In testimony that I claim the foregoing material to be my invention, I have signed my name in

5 to 7. In an embroidery frame, means for holding the material to be embroidered, comprising a channel bar and a spring rod disposed in said channel bar, said spring rod

10 being bowed in its untensioned position, and

means for holding said spring rod tensioned

THEODOR D. EISNER.
